FOOT MEASURING DEVICE

Russell Plato Schwartz, Rochester, N. Y.

Application March 11, 1936, Serial No. 68,266

7 Claims. (Cl. 33—3)

Freedom from foot strain is essential for foot comfort in normal walking and standing. The relationship of the muscles forming the calf of the leg (the gastrocnemius and soleus) is a matter of primary importance in obtaining such foot comfort. Under modern conditions, many women have become accustomed to wearing shoes with a heel height greater than one and one-half inches. This frequently results, over 10 a period of time, in an adaptive or acquired shortening of the above mentioned calf muscles. When the muscles have thus been shortened, it is no longer possible to dorsi-flex the foot to the normal extent when the leg is extended 15 straight, as in standing or walking. Full or straight extension of the leg at the knee joint has a tendency to tighten the gastrocnemius muscle and, accordingly, the foot condition should be determined when the leg is thus fully 20 extended, rather than when it is bent, as in sitting.

Normal muscle structure should make it possible to dorsi-flex the foot, without strain, to about 110°, when the leg is fully extended. To 25 permit the wearing of shoes with no heels, without muscle strain, the muscle structure should be such that the person can dorsi-flex the foot to at least 90° without feeling any strain. But when the calf muscles have become shortened, 30 as above mentioned, then it is frequently impossible for the person to dorsi-flex the foot as much as 90° (with the leg fully extended) without producing undesirable muscle strain. In order to provide shoes which will be comfortable 35 and will avoid muscle strain when the person is walking or standing, it is highly important to determine the extent to which the foot can be dorsi-flexed, without producing muscle strain, in order to determine the minimum height of 40 heel with which the shoe should be equipped for the avoidance of strain. This is equally true whether the inability to dorsi-flex the foot to the full normal amount is due to acquired or adaptive shortening on account of long continued wearing of high heels, or is due to malformations or other conditions.

A primary object of the invention is, therefore, to provide, a simple and compact device for 45 determining the minimum heel height which should be provided on shoes for any particular person.

Another object is the provision of such a device which is light in weight, of few parts, easy 50 and inexpensive to manufacture, and which can

be readily used effectively by relatively unskilled persons.

To these and other ends the invention resides in certain improvements and combinations of parts, all as will be hereinafter more fully described, the novel features being pointed out in the claims at the end of the specification.

In the drawing:

Fig. 1 is a side view of a foot measuring device constructed in accordance with a preferred embodiment of the invention;

Fig. 2 is a bottom view thereof;

Fig. 3 is an end view thereof;

Fig. 4 is a view showing the device as used in measuring a foot requiring one shoe heel height, 15 and

Fig. 5 is a view similar to Fig. 4 showing the measuring of a foot requiring a greater shoe heel height.

The same reference numerals throughout the 20 several views indicated the same parts.

The device comprises a bar or member having a relatively long arm 10 of a substantial width to lie against the back or posterior aspect of the leg, and long enough to extend up at least to the 25 calf of the leg, as indicated in Figs. 4 and 5. In order to assist in maintaining the position of this bar 10 along the back of the leg during the measuring operation, the bar may be provided with lateral extensions, projections, arms, or 30 brackets 11 and 12, curved outwardly and upwardly as shown, the member 11 lying, for example, against one side of the person's leg adjacent the ankle and the member 12 lying, for 35 example, against the opposite side of the person's leg adjacent the calf.

The device further includes an arm or member 14 for contact with the sole of the foot adjacent the toes thereof, or as least as far forwardly as the ball of the foot or the little toe. This member 14 may conveniently be made integrally of the same wide flat strip of metal as the member 10, so that it is immovable or in fixed 40 position relatively to the member 10, at a definite 45 predetermined angle thereto. Conveniently, the outer end of the member 14 is at 90° to the member 10, as shown in Fig. 1, while the inner end of the member 14 closer to the member 10 is at a slightly greater angle to the member 10, say, 50 for example, about 95° or 100° as shown.

A member 16, slidably mounted on the member 10, projects therefrom in the same direction as the member 14 but to a lesser extent, for contact with the heel portion of the sole of the per- 55

son's foot, as shown in Figs. 4 and 5. This member 16 is slidable back and forth along the member 10 to different extents toward and away from the member 14. Cooperating graduations on the member 10 and the member 16 are provided, such as the scale markings 18 on the member 10 and the line or index point 19 on the slide 16, conveniently formed by an edge of a portion of the member 16.

10 In use, the person whose foot is to be measured usually sits down and is asked to extend the leg straight substantially horizontally, as indicated in Figs. 4 and 5. In such straight position of the leg, the calf muscles are tensioned to the same extent as when standing or walking. Then the bar 10 is applied to the posterior aspect of the leg and moved upwardly until the member 14 contacts with the sole of the foot adjacent the ball of the foot or the little toe. The person is 15 asked to dorsi-flex his foot to the maximum extent possible without producing unpleasant muscle strain. If, when this is done, the heel comes down into contact with the bar 14, it is known that the foot can dorsi-flex to at least 90°, and, 20 therefore, it is possible for this person to wear shoes with no heels at all, if desired. On the other hand, if the maximum dorsi-flexed position of the foot leaves the heel still some distance from the bar 14, as in Figs. 4 and 5, then the 25 member 16 is moved upwardly along the bar 10 until it is in contact with the heel, as in Figs. 4 and 5, and is held in position by the fingers until the device is removed from the leg. Then the 30 scale markings 18 are read to determine the position of the movable member 16 relatively to the members 10 and 14, and thus to determine the minimum heel height which should be provided in shoes to be worn by this person to avoid muscle strain. Fig. 4 illustrates the measuring of a 35 foot which requires heels of a substantial minimum height, while Fig. 5 illustrates the measurements on a foot requiring heels of an even greater height due to the inability of the foot to dorsi-flex sufficiently to permit the use of low shoe 40 heels.

The graduations 18 shown in Fig. 2 are graduated to read directly in terms of inches and fractions of inches of heel height required, but obviously any other suitable graduations, in any 45 known or predetermined units of measurement, may be employed.

It will be apparent that the member for contacting with the toe portion of the sole of the foot could be movable relatively to the bar 10, and the member for contacting with the heel portion of the sole of the foot could be fixed relatively to the bar 10, such a reversal being obvious to those skilled in the art, but it is ordinarily preferred to make the device in the form above described, 50 with the member for contacting with the toe portion a fixed member, and with the member for contacting with the heel portion a movable member.

While one embodiment of the invention has 55 been disclosed, it is to be understood that the inventive idea may be carried out in a number of ways. This application is, therefore, not to be limited to the precise details described, but is intended to cover all variations and modifications thereof falling within the spirit of the invention or the scope of the appended claims.

I claim:

1. A relatively light, portable foot measuring device for measuring a foot when the leg is 60 extended approximately horizontally without

weight thereon, comprising a member for contacting with and extending a substantial distance along the lower portion of a person's leg when the leg is extended substantially straight, a laterally extending arm in fixed position relatively to said member for contact with the under side of the forward part of the foot, and means freely slidable along said member for contact with the bottom of the heel of the foot to measure various positions thereof relatively to said member and arm. 10

2. A relatively light, portable foot measuring device for measuring a foot when the leg is extended approximately horizontally without weight thereon, comprising a member for extending a substantial distance along and in contact with the posterior aspect of the leg, a lateral extension on said member for contact with the side of the leg, and an arm extending laterally from said member at an angle to contact with the sole of the foot both at the heel portion thereof and at the forward portion thereof when the foot is dorsi-flexed to a predetermined angular extent, to test the ability of the foot to dorsi-flex to said extent. 15

3. A portable foot measuring device for easy application to a foot on a leg extending approximately horizontally, comprising a member for extending a substantial distance along and in contact with the posterior aspect of the leg, a lateral extension on said member for contact with the side of the leg, an arm extending laterally from said member at an angle to contact with the sole of the foot both at the heel portion thereof and at the forward portion thereof when the foot is dorsi-flexed to a predetermined angular extent, to test the ability of the foot to dorsi-flex to said extent, and movable means for contact with said heel portion of the sole when said arm is in contact with the forward portion of the sole and when said foot is dorsi-flexed to a less extent than said predetermined angular extent. 30

4. A foot measuring device comprising a relatively light, readily portable bar for application to the foot and lower part of a leg positioned approximately horizontally, said bar having two arms arranged substantially at right angles to each other, one of said arms being substantially longer than the other and long enough to reach from the sole of a person's foot up the back of the person's leg at least as far as the calf thereof, the shorter arm being long enough to extend from the longer arm, when so positioned on the person's leg, at least as far as the ball of the foot, means on said longer arm for engaging the sides of the leg to assist in holding said longer arm in proper position against the back of the leg, a member movable along said longer arm for contact with the bottom of the person's heel, and scale means for reading various positions of said heel contacting member along said longer arm in terms of predetermined units of measurement. 45

5. A light, portable device for determining the minimum height of shoe heel which should be 55 worn by a person to avoid muscle strain, said device comprising means for extending a substantial distance along the lower leg when the leg is extended substantially straight in an approximately horizontal position, means for contacting with the sole of the person's foot adjacent the toes, other means for contacting with the sole of the person's foot at the heel portion thereof when the foot is dorsi-flexed to a point just short of that producing muscle strain, said 60

two means for contacting with the sole being movable relatively to each other, and scale means for reading the position of one of said sole contacting means relatively to the other thereof, to 5 determine the minimum height of shoe heel which should be worn.

6. A portable device for determining the minimum height of a shoe heel which should be worn by a person to avoid muscle strain, said device 10 comprising a relatively light, generally L-shaped rigid bar having two arms of unequal length, the longer of said arms being sufficiently long to extend from the heel of a foot along the posterior aspect of the leg at least as far as the calf 15 of the leg, the shorter of said arms being sufficiently long to extend from said longer arm along the sole of the foot at least as far as the ball of the foot, said L-shaped bar being intended to be held by hand and manually applied to the 20 foot when the leg is positioned approximately horizontally so that the foot does not carry a load,

a member slidable along said longer arm of said bar and projecting laterally therefrom for contact with the heel of the foot to be measured when the ball of such foot is in contact with said shorter arm, and scale means for reading the position of said laterally extending member in terms of predetermined units of measurement, to determine the proper minimum heel height. 5

7. A construction according to claim 6 further including a laterally extending member secured to said longer arm of said bar near the end thereof remote from said shorter arm, to contact with one side of the leg to which the device is applied near the calf of such leg, and another laterally extending member secured to said longer arm of said bar intermediate its length to contact with the opposite side of such leg adjacent the ankle thereof, to assist in positioning said device upon the leg. 10 15
